Primary Examiner — Cynthia Ramirez*Assistant Examiner* — Laura Yu(74) *Attorney, Agent, or Firm* — Studebaker & Brackett PC(57) **CLAIM**

The ornamental design for the motor, as shown and described.

DESCRIPTION

FIG. 1 is a perspective view of the front, right and top sides of a motor showing our new design;

FIG. 2 is a perspective view of the rear, left and bottom sides thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken line showing of the motor is included for the purpose of illustrating portions of the motor and forms no part of the claimed design. The dot and dashed lines set forth boundaries between the claimed portion and the unclaimed portion of the motor.
